DESIGN FOR A COMBINED BASE AND COLUMN FOR LAMPS

Dorothy Shepard, Providence, R. I., assignor to
Electrical Testing Laboratories, New York, N. Y.,
a corporation of New York

Application August 11, 1938, Serial No. 79,252

Term of patent 3½ years

To all whom it may concern:

Be it known that I, Dorothy Shepard, a citizen of the United States of America and a resident of Providence, in the county of Providence and State of Rhode Island, have invented a new, original, and ornamental Design for a Combined Base and Column for Lamps, of which the following is a specification, reference being had to the accompanying drawing, forming a part thereof.

Figure 1 is a side elevational view of a combined base and column for lamps, showing my new design, and

Figure 2 is a top plan view thereof.

I claim:

The ornamental design for a combined base and column for lamps, as shown.

DOROTHY SHEPARD.
